Filed July 10, 1964, Ser. No. 80,806

Term of patent 14 years

(Cl. D80—11)

FIG. 1 is a top plan view of a combined illuminable map, tourist guide, and advertising cabinet embodying my new design;

FIG. 2 is an elevational view of the cabinet taken from the right side thereof;

FIG. 3 is an elevational view of the cabinet taken from the left side thereof;

FIG. 4 is a bottom plan view of the cabinet;

FIG. 5 is a rear elevational view of the cabinet; and

FIG. 6 is a cross sectional view taken on line 6-6 of FIG. 1.

The dominant features of my design reside in the portions shown in full lines.

I claim:

The ornamental design for a combined illuminable map, tourist guide and advertising cabinet, as shown and described.
